(72) Inventor: **Joseph Daniel Tippmann**, Fort Wayne, IN (US)

Primary Examiner — Mary Ann Calabrese

(74) Attorney, Agent, or Firm — Dunlap Bennett & Ludwig PLLC; Brendan E. Squire

(**) Term: **15 Years**

(21) Appl. No.: **29/633,615**

(22) Filed: **Jan. 15, 2018**

(57) **CLAIM**

The ornamental design for a desktop with concealable workspace, as shown and described.

DESCRIPTION

(63) Continuation-in-part of application No. 15/371,918, filed on Dec. 7, 2016, now abandoned.

FIG. 1 is a top front perspective view of a desktop with concealable workspace showing my new design in a closed condition;

(51) **LOC (12) Cl.** **06-06**

FIG. 2 is a lower front perspective view thereof;

(52) **U.S. Cl.**

FIG. 3 is a top plan view thereof;

USPC **D6/707.19**

FIG. 4 is a bottom plan view thereof;

(58) **Field of Classification Search**

FIG. 5 is a front elevation view thereof, the rear elevation view being a mirror image thereof;

USPC D6/641, 644, 655, 655.17, 18, 685, 686,

FIG. 6 is a left side elevation view thereof; the right side elevation view being a mirror image thereof;

D6/691, 691.1–691.19, 707, 707.19

FIG. 7 is a top front perspective view of the desktop with concealable workspace in an open condition;

CPC A47B 1/00; A47B 1/02; A47B 1/05; A47B

FIG. 8 is a lower front perspective view thereof;

1/10; A47B 5/00; A47B 7/00; A47B

FIG. 9 is a front elevation view thereof;

13/00; A47B 13/08; A47B 13/081; A47B

FIG. 10 is a rear elevation view thereof;

13/088; A47B 13/10; A47B 13/12; A47B

FIG. 11 is a top plan view thereof;

17/00; A47B 17/036; A47B 17/04; A47B

FIG. 12 is a bottom plan view thereof;

17/06; A47B 21/00; A47B 2200/0001;

FIG. 13 is a left side elevation view thereof; the right side

A47B 2200/0066

elevation view being a mirror image thereof;

See application file for complete search history.

FIG. 14 is an exploded front perspective view thereof; and,

(56) **References Cited**

FIG. 15 is an exploded rear perspective view thereof.
